Patented Jan. 2, 1917.

UNITED STATES PATENT OFFICE.

JOHN BRANDWOOD, THOMAS BRANDWOOD, AND EDWARD BRANDWOOD, OF BURY,
ENGLAND.

PERFORATED BEAM FOR DYEING AND LIKE APPARATUS.

1,211,068.

Specification of Letters Patent.

Patented Jan. 2, 1917.

Application filed October 27, 1914. Serial No. 363,842.

To all whom it may concern:

Be it known that we, JOHN BRANDWOOD, THOMAS BRANDWOOD, and EDWARD BRANDWOOD, subjects of the King of Great Britain and Ireland, and residents of Bury, in the county of Lancaster, England, have invented new and useful Improvements in Perforated Beams for Dyeing and like Apparatus, of which the following is a specification.

This invention relates to improvements in the construction of perforated beams or the like upon which warps are dyed or subjected to other liquid treatment. Such beams are so formed and constructed that the parts which come into contact with the warps are of such a nature and substance as not to be affected by the liquid used, so that no deterioration of the yarn takes place by contact with the beam, while those parts of the beam which do not come into contact with the yarn are composed of iron or other cheap and strong metal hereinafter referred to as iron. The substance which is not affected by the liquids is usually nickel or nickel alloy and will be hereinafter referred to as nickel. In a known form of such beam the flanges at the ends of the beam are formed of rings or annular plates of nickel, mounted on an iron hub. A considerable thickness of nickel had to be used in such flanges as they bore unsupported for a considerable part of their areas the pressure exerted by the wound yarns, and because when the beam was placed and rolled on a floor or other surface these nickel flanges had to support the weight of the beam. To enable them to withstand the stresses so put upon them the nickel flanges had to be of considerable thickness and weight and were consequently expensive.

This invention consists in backing up the protective nickel flange, or an equivalent element or surface composed of substance unaffected by the liquid used in the process, by a supporting strong iron flange which extends the full diameter of the nickel flange or equivalent element or surface (hereinafter generally referred to as a nickel flange) and which preferably extends to a diameter which is slightly greater than the diameter of the nickel flange so as to come into contact with the floor or other surface, when the beam is laid down or rolled. The nickel flange or

facing, or lining as it becomes, may thus be very thin.

The invention also relates to a mode or means for securing the nickel flange or facing to its supporting iron flange so that liquid cannot penetrate between the two. With the thin nickel flanges or faces which can be used on a beam according to this invention a very considerable saving in cost is effected.

The accompanying drawings illustrate a beam flange constructed according to this present invention.

Figure 1 shows it half in section along its axis and half in elevation. Fig. 2 shows it in elevation from the outside face and from the inside face respectively in its left and right halves. Fig. 3 is a sectional view showing a detail of the eye or center of the flange. Fig. 4 is a sectional detail showing the periphery of the flange. Fig. 5 is a sectional detail of the periphery of a flange illustrating a modification in the means for securing the nickel flange in place.

A indicates the iron flange formed on its outer face with a cylindrical or slightly coned portion B which when the contents of the beam are being dyed fits upon a seat surrounding the dye inlet or outlet. The flange is of the full diameter that yarn will be wound to upon the beam to which the flange is fixed.

C are spokes by which the beam is secured to the loom shaft or the like, and D indicates a seat in which the end of the perforated cylindrical shell E of the beam is secured in place. The complete beam comprises a perforated cylindrical shell with a flange on each end.

On the inner face of the flange A is a thin plate F of nickel. It is in the form of a ring or annulus and its inner edge is spun or pressed over into the groove G in the eye of the flange, and its outer edge is spun over into the groove G¹ on the outer periphery of the iron flange. See Figs. 1, 3 and 4. The spinning or pressing may be sufficient to maintain liquid tight joints between the peripheries of the nickel plate F and the iron flange A, and thus prevent the ingress of liquor between the plate and the flange, or additional means for securing them may be employed. That part of the eye of the flange A over which the plate F is turned

- before it reaches the groove G may be of slightly larger diameter than the remainder of the seat D for the end of the shell E, being only sufficiently larger that when the 5 plate F is in place on the flange the diameter of the eye is the same from end to end with the exception of the groove G. When the cylindrical end of the perforated shell is forced in place in the seat D the nickel 10 is held firmly against the surrounding iron. The outer edge of the nickel plate may be additionally secured in place in its groove by means of a wire H which is bound tightly around it.
- 15 In the modification shown in Fig. 5 the outer periphery of the nickel flange F is pressed over the periphery of the iron flange A and is secured in place by an endless and tight fitting nickel ring H' which is forced 20 in place over it, and is of less diameter than the part a.
- The periphery of the iron flange A may project around one face to a greater extent from its center than it does at that part 25 which is covered by the nickel plate and as shown at a in Figs. 1 and 4. With such a formation of its flanges a beam would roll along a floor or other surface on the iron parts a and the nickel parts would be kept 30 out of contact with such floor or surface.
- If desired the protective thin nickel flange or facing on the inner face of the iron flange A may be otherwise applied than as described, or it may be replaced by other sub- 35 stances which is similarly protective and resistant. For example the inner face of the iron flange may be covered with a suitable enamel.
- As another example the thin protective 40 facing or surface for the flange may consist of hard rubber or ebonite. The dough may be vulcanized in place upon the iron foundation or sheet ebonite already vulcanized may be applied to the face of the disk in any 45 suitable manner. Cement may be applied to join the hard rubber to the metal or the peripheries of the sheet or disk of hard rubber may be secured in place by any suitable mechanical devices. The peripheries may 50 be bent over in the manner of the nickel disk if they are softened in boiling water. Or hard rubber disks may be molded and vulcanized with bent or flanged peripheries.
- What we claim is:—
- 55 1. In a perforated beam for dyeing or like apparatus a flange at the end of the beam comprising a thin protective facing

and an iron backing for such facing, the 60 backing being at least the full diameter of the facing, substantially as hereinbefore described.

2. In a perforated beam for dyeing and like apparatus a flange at the end of the beam comprising a thin protective facing and an iron backing for such facing, the 65 backing being of larger diameter than the facing, substantially as hereinbefore described.

3. In a perforated beam for dyeing and like apparatus a flange at the end of the 70 beam comprising an iron foundation and a thin nickel covering plate on the inner face, substantially as described.

4. In a perforated beam for dyeing and like apparatus a flange at the end of the 75 beam comprising an iron foundation and a thin nickel covering plate the edges of which are spun or pressed into contact with the iron foundation, substantially as hereinbefore described.

5. In a perforated beam for dyeing and like apparatus a flange at the end of the beam comprising an iron foundation and a thin nickel covering plate of less diameter, the edges of which are pressed into contact 85 with the iron foundation, substantially as hereinbefore described.

6. In a perforated beam for dyeing and like apparatus, a flange at the end of the beam comprising an iron foundation and a 90 protective covering therefor, the said foundation being permanently formed on its outer face with a member for making a fluid tight joint to prevent access of dye liquid and consequent deterioration of said foundation, substantially as described.

7. A beam upon which yarns are dyed or similarly treated, such beam having a perforated cylindrical part and having a strong iron flange at each end lined with a thin 100 protective lining permanently so secured to the iron foundation that the dye liquid cannot have access to the iron flange, substantially as described.

In witness whereof we have hereunto set 105 our hands in the presence of two subscribing witnesses.
